UNITED STATES PATENT OFFICE.

BRADLEY A. FISKE, OF NAPERVILLE, ILLINOIS, ASSIGNOR TO EBERHARD FABER, OF PORT RICHMOND, NEW YORK.

PEN-HOLDER.

SPECIFICATION forming part of Letters Patent No. 255,272, dated March 21, 1882.

Application filed December 15, 1881. (No model.)

To all whom it may concern:

Be it known that I, BRADLEY A. FISKE, a citizen of the United States, residing at Naperville, in the county of Du Page and State 5 of Illinois, have invented new and useful Improvements in Pen-Holders, of which the following is a specification.

This invention relates to what are known as "shooting pen-holders," wherein the pen may 10 be liberated and discharged without taking hold of it, as in ordinary holders; and it consists in the combination of a sheet-metal pen-holding spring, having a flat shank and a segmental tip, with a handle having a longitudinal 15 groove extending upward from its lower end for the reception of the spring, and a means for attaching the shank of the spring to the handle, so that, while the pen may be inserted for use in the slit or socket formed between 20 the tip of the spring and the bottom of the groove in the handle, the spring is adapted to be forced away from the groove for discharging the pen. The pen-holding spring has thumb-ears projecting laterally from the tip 25 thereof for its manipulation; and the means for attaching the shank of the spring to the handle consists of a sleeve having the spring secured thereto, such sleeve being fitted loosely on the handle, so that it, together with the 30 spring, can be entirely removed from the handle for dislodging the pen in case it sticks or adheres to the parts.

This invention is illustrated in the accompanying drawings, in which Figure 1 represents a side view. Fig. 2 is a like view, looking in an opposite direction to Fig. 1. Fig. 3 is a longitudinal central section, and Fig. 4 a cross-section through the tip end.

Similar letters indicate corresponding parts. 40 The letter A designates the pen-holding spring; A' the shank, A'' the tip, and A''' the thumb-ears, of the spring. B denotes the handle, B' its groove, and C the attaching-sleeve.

The spring A is formed of steel or other suitable sheet metal, and the shank A' thereof is left flat to preserve its elasticity, while the tip 45 A'' is made segmental in cross-section, thus

conforming to the cross-section of a pen. The ears A''' project laterally from the tip A'', one on each side thereof, the same extending beyond the side of the handle. 50

The groove B' of the handle extends upward from its lower end a sufficient distance to receive the spring A, and the bottom of the groove is formed substantially in conformity 55 with the cross-section of the spring—namely, with a flat seat or portion to receive the shank A' and with a segmental grooved portion to receive the tip A''. That portion of the handle B containing the groove B' is chamfered 60 or cut away lengthwise in a curved line, and the spring A is bent longitudinally to correspond with such curvature, as shown in Fig. 3, in order to reduce the bulk or thickness of 65 the article at the point.

The sleeve C is fitted loosely on the handle B, and the shank A' of the spring is secured thereto by a rivet, o, or other suitable means, such shank being under or within the sleeve. In placing the sleeve C on the handle it should 70 be held in such a position that the spring A is received in the groove B', and if a pen is then inserted into the slit formed between the tip A'' and the bottom of the groove it is firmly retained in position by the pressure of the 75 spring. When it is desired to remove the pen the tip A'' is forced away from the groove B', as by taking hold of the thumb-ears A''', thus liberating the pen, and if the latter then fails to drop out from its seat, as by adhesion due 80 to the ink used, the sleeve C is simply slid off from the handle, thus entirely detaching the spring.

It should be remarked that the spring A can be attached to the handle by other readily- 85 devisable means than the sleeve C, and, if desired, it can be permanently attached.

What I claim as new, and desire to secure by Letters Patent, is—

1. A pen-holder combining in its structure 90 a wooden staff or handle, provided at one end, on its under side, with a segmental-shaped groove, terminating at its inner portion in a flat seat, and a longitudinally-bent spring hav-

- ing a segmental-shaped tip and a flat end, resting respectively in the segmental groove and on the flat seat of the staff or handle, substantially as and for the purpose described.
- 5 2. The combination, substantially as hereinbefore set forth, of the sheet-metal pen-holding spring, having a flat shank, segmental tip, and thumb-ears projecting laterally from the tip, with the handle, having a longitudinal
- 10 groove extending upward from its lower end for the reception of the spring, and means for attaching the spring to the handle.
3. The combination, substantially as herein-

before set forth, of the sheet-metal pen-holding spring, the handle, having a longitudinal groove extending upward from its lower end for the reception of the spring, and the attaching-sleeve, having the spring secured thereto, such sleeve being fitted loosely on the handle.

In testimony whereof I have hereunto set 20 my hand and seal in the presence of two subscribing witnesses.

BRADLEY A. FISKE. [L. S.]
